UNITED STATES PATENT OFFICE.

JESSE S. WENTWORTH, OF NORWOOD, OHIO.

CAN-FORMING MANDREL.

1,342,575.

Specification of Letters Patent.

Patented June 8, 1920.

Application filed March 11, 1918. Serial No. 221,611.

To all whom it may concern:

Be it known that I, JESSE S. WENTWORTH, a citizen of the United States of America, and resident of Norwood, in the county of 5 Hamilton and State of Ohio, have invented a new and useful Improvement in Can-Forming Mandrels, of which the following is a specification.

An object of my invention is to produce 10 a mandrel upon which cans of paper or other fibrous material may be constructed, the walls of the mandrel being adapted to be expanded previous to the construction of the can and to be contracted to remove the 15 completed can.

A further object is to produce a mandrel adapted to be expanded and contracted in the can forming and removing operations, to be subjected to vacuum pressure during 20 the can forming operation, and to be subjected to positive pressure during the can removing operation.

These and other objects are attained in the mandrel described in the following 25 specification and illustrated in the accompanying drawings, in which:

Figure 1 is a longitudinal sectional view of a mandrel embodying my invention.

Fig. 2 is an end elevation of my improved 30 mandrel.

Fig. 3 is a transverse sectional view taken on the line 3—3 of Fig. 1 portions of the spring being broken away.

Fig. 4 is a transverse elevation upon the 35 line 4—4 of Fig. 1.

Fig. 5 is an elevation of my improved mandrel and a vertical sectional view of the mechanism adapted to operate it.

Fig. 6 is a sectional view of a can which 40 has been constructed upon and removed from the mandrel shown in Fig. 1.

My improved mandrel consists of a core comprising a shaft 7 and a sleeve 8 mounted upon the shaft, a hinge block 9 secured to 45 the sleeve by means of screws 10 and 11, and wings 12 and 13 which are operated to expand or contract the mandrel, by means of a wedge 14 which is operated from a reciprocally mounted key 15 located in the 50 shaft. Sleeve 8 is secured to shaft 7 by means of screws 10 and 11 which pass through block 9 as well as the sleeve and into the shaft. At each side the block is provided with lugs 16 which coöperate with 55 lugs 17 on wings 12 and 13 for pivoting the wings, the outer surfaces of the wings form-

ing a true circle with the curvature of block 9 when they are in expanded position as shown in Figs. 3 and 4, and the inner surfaces of the wings conforming with the true 60 circle of the sleeve 8 when in contracted positions as shown in dotted lines in Fig. 3. The ends of wings 12 and 13 are beveled to conform to the angle of wedge 14 so as to cause expanding and contracting movement 65 of the wings when the wedge is moved radially. A spring 18 is provided for retaining the wings 12 and 13 in engagement with the wedge when in their expanded position and in engagement with the sleeve when in 70 their contracted position. This spring is attached to webs 19 and 20 formed upon the interior of the wings, and is stretched across a space 21 which is provided by removing a portion of sleeve 8 between its 75 ends 22 and 23 as shown in Figs. 1 and 3. Wedge 14 is provided with a pair of guides 24 and 25 which guide it when being moved radially. A pair of lugs 26 and 27 are located between the guides 24 and 25 for 80 attachment to links 28 and 29 of pairs of toggle links, the coöperating links 30 and 31 of which are connected to pairs of lugs 32 and 33 formed on sleeve 8 as shown in Fig. 3. At their connected ends the links are 85 connected to links 34 and 35, the opposite ends of which are connected to lugs 36 and 37 extending from the key 15. Thus when the key 15 is reciprocated in its mounting way 38, the wedge is caused to move the 90 wings to mandrel-expanding position or to position to permit the wings to contract the mandrel under the influence of spring 18. Upon the end of the mandrel I mount a plate 39 which is of a diameter equal to that 95 of the mandrel when contracted. For the purpose of assisting in the construction of cans upon my improved mandrel, as well as in their removal therefrom, I have provided an air passage 40 passing through the shaft 100 and communicating with branch passages 41 extending through end plate 39 as well as a branch passage 42 which connects with a series of passages 43 extending through block 9.

In order to illustrate the operation of my improved mandrel, I have illustrated in Fig. 5 a form of mechanism adapted to operate the mandrel. A spider 44 is mounted upon a shaft 45 and is adapted to mount 110 shaft 7 of the mandrel rotatively. A pinion 46 is secured to shaft 7 and is driven by a

large gear 47 from shaft 45. To effect expanding and contracting movement of the mandrel I have shown a grooved collar 48 connected with key 15 of the mandrel and 5 have provided a yoke 49 which is operated from a lever 50 which carries a roller 51 at its end. Roller 51 operates upon a cam 52 which is adapted to be rotated to cause retraction of key 15 and consequently wedge 10 14 to effect collapsing movement of the mandrel. A spring 53 is provided to return the lever and consequently the key and wedge to mandrel-expanding position, or vice versa.

15 In the operation of my improved mandrel during the making of a can thereon, the mandrel is expanded. The bottom 55 of the can is now placed over end plate 39 and the strip of paper from which the can is constructed is now placed in contact with the openings 43 and air suction is created through passages 40, 41, 42 and 43. The mandrel rotation being continuous, the paper is wound around the bottom and mandrel until the required thickness of can shell 54 is produced. The projecting edges of the bottom and body are then spun over one another to produce the beaded bottom shown in Fig. 6. After the can has thus been 20 25 30 35 constructed, the mandrel is collapsed to free the can, and by any suitable means, as by air blown through the passages 40, 41, 42 and 43, the can is discharged from the mandrel.

Having thus described my invention, what

35 I claim is:

1. A can-forming mandrel consisting of a core, wings pivotally mounted on the core, a key reciprocally mounted in the core, a wedge reciprocally mounted for movement 40 between the wings, and a toggle joint between the key and wedge, adapted to effect wing-spreading movement of the wedge when the key is operated.

2. A can-forming mandrel consisting of 45 a core, wings pivotally mounted on the core,

a key reciprocally mounted in the core, a wedge reciprocally mounted for movement between the wings, a toggle joint operatively connected with the key and wedge, adapted to effect wing-spreading movement of the 50 wedge, and a spring connecting the wings, adapted to retract them to normal position when the wedge is withdrawn.

3. In a can-forming mandrel the combination of a core comprising a shaft, a sleeve 55 upon the shaft, and a hinge block secured to the core, said parts of the core having air passages in them adapted to form a part of a vacuum system, wings pivoted to the hinge block, and means for moving the wings to 60 expand and contract the mandrel.

4. A can-forming mandrel comprising a core consisting of a series of relatively stationary parts, and a series of relatively movable parts connected with the core, the 65 outer faces of certain of said stationary parts and of said movable parts forming the surfaces of the mandrel, said stationary parts having air passages therein communicating with the outer surfaces of said parts. 70

5. A can-forming mandrel consisting of a core having a portion of the surface thereof adapted to form the outer surface of the mandrel, wings pivoted on the core and having the outer surfaces thereof adapted to 75 complete the outer surface of the mandrel when in collapsed condition, and a wedge adapted to spread the wings to expand the mandrel and having a portion of the surface thereof adapted to form a portion of the outer surface of the mandrel when the wings are expanded.

In testimony whereof, I have hereunto subscribed my name this 9th day of March, 1918.

JESSE S. WENTWORTH.
